UNITED STATES PATENT OFFICE

CLARENCE WARNER, OF DAYTON, OHIO, ASSIGNEE, BY MESNE ASSIGNMENTS, TO
FRIGIDAIRE CORPORATION, A CORPORATION OF DELAWARE

REFRIGERATING APPARATUS

Application filed March 6, 1926. Serial No. 92,794.

This invention relates to improvements in sealing devices and particularly to the type of sealing devices used in connection with rotating shafts included in compressors or like devices where it is desirable to have a tight joint between its rotating shaft and the case, or support, in which it operates.

In the particular form in which the invention is herein illustrated a single cylinder compressor is shown, such as is used in connection with small refrigerator units for compressing the refrigerant. The compressor includes a crankcase and a crankshaft or driving shaft journaled in bearing bosses provided in the walls of said crankcase, one end of said crankshaft extending through a wall of the crankcase and having means secured thereto for driving the compressor. In machines of this type the refrigerant is usually drawn into the crankcase of the compressor and then by-passed to the cylinders and there compressed. It is important, therefore, that the crankcase shall be both fluid and gas tight.

One of the objects of the present invention is to produce a structure that will obtain such tightness of the crankcase and maintain it through a long period of operation of the compressor.

Further objects and advantages of the present invention will be apparent from the following description, reference being had to the accompanying drawing, wherein a preferred form of the present invention is clearly shown.

Referring to the drawing in which the device is shown in cross section, certain portions, however, being shown in elevation for the sake of clearness, the numeral 20 designates the cylinder of the compressor, having a flange 21. The flange conforms with and is adapted to fit on the open end of the crankcase 22, a gasket 23 being provided therebetween to prevent leakage at this point. Studs 24 hold the cylinder 20 in position on the crankcase which contains the refrigerant and a proper amount of lubricant.

Extending inwardly from opposite side walls of the crankcase are two aligned, bearing bosses 25 and 26 in which the drive shaft 27 is journaled. Grooves 28 and 29 formed

in bosses 25 and 26 respectively, serve to keep the drive shaft journals lubricated. Between the bearing bosses 25 and 26 the shaft 27 is provided with an eccentric collar 30 mounted thereon, said collar being secured to the shaft 55 by means of a key 31.

A piston 32 is provided in the cylinder 20, said piston having a connecting rod 33 which is operatively connected with the eccentric collar 30 in any suitable manner.

Bearing boss 25 has a key way 34, which is provided for the purpose of assembling the connecting rod and its eccentric collar to the shaft 27. In the assembling operation the piston is first placed in the cylinder. The cylinder is then placed in position on the crankcase, the eccentric collar being aligned with the bearing boss 25 so that the key way 35 in the eccentric collar, is in direct alignment with the key way 34 in the bearing bosses. The drive shaft 27 including the key 31 is then inserted in the passage of boss 25 the key 31 passing through the keyway 34 and entering the keyway in the eccentric collar. Extending outwardly from the side 75 walls of the crankcase are annular extensions formed coaxial with the bearing bosses, said annular extensions forming housing portions on the outside of the crankcase. The annular extension 40 formed on the right side of the crankcase, as shown in the drawing, has its recessed portion provided with screw threads 41 into which the nut 42 is adapted to be screwed. This nut 42 is hollowed out to receive a coil spring 44, one end of which abuts 80 against the inner wall of said nut. Interposed between the other end of spring 44 and the end of drive shaft 27, which end extends slightly into the annular extension 40, are two washers 45, the engaging faces of said washers being spherical in shape so as to reduce the area of the contacting surfaces therebetween and thus substantially reduce friction. In the operation of the compressor the washer engaging with the drive shaft 27 90 will be carried along by friction and will rotate therewith while the washer engaging with the spring will be held substantially stationary.

The annular extension 49 on the left side 100

of the crankcase, as shown in the drawing, has a flange 50, which is provided with apertures for receiving studs 51. The flange 50 of the annular extension has a slight protuberance 52 which is ground for the purpose of providing a smooth surface for the packing gasket 53.

The drive shaft 27 is provided with a circumferential flange 54, which, when the shaft 10 is in proper assembled position lies inside the annular extension 49 adjacent the inner walls thereof. A bearing ring 55 of any suitable bearing metal preferably of the self-lubricating type comprising a porous metal adapted to be impregnated with a lubricant surrounds the shaft 27 and engages with the outer surface of flange 54 in sealing relation therewith, the bearing ring being supported by the peripheral flange 57 of a retaining member or ring 56 carried by a diaphragm as hereinafter described.

A diaphragm 58, provided with a central opening, fits over shaft 27, the inner edge of said diaphragm being spun over the inner 25 edge of retaining or sealing ring 56. This inner edge of the diaphragm is secured to the retaining or sealing ring in any suitable manner such as by welding or soldering. The outer edge of the diaphragm lies adjacent the packing gasket 53.

A clamping gland 60 is provided having apertures for receiving the studs 51. When the studs 51 are drawn up the clamping gland is pulled toward the flange 50 of the 35 annular extension 49, thus tending to clamp the packing gasket 53 and the edge of the diaphragm 58 tightly between the ground surface of the protuberance 52 and said clamping gland 60. This provides a tight 40 joint which will tend to prevent the leakage of fluid or gas at this point of connection.

The clamping gland 60 has a central aperture 61 through which the shaft 27 extends. The inner surface of this aperture is 45 spherical as illustrated at 62, forming a seat for the spherical surface of supporting ring 63 which also surrounds shaft 27 and is interposed between the diaphragm 58 and the clamping gland 60. The spherical surfaces 50 at 62 on both the clamping gland 60 and the supporting ring 63 provide means whereby, when one of the studs 51 is drawn tighter than the other and the clamping gland 60 is not in absolute alignment with the diaphragm 58, the ring 63 may move relative to said clamping gland 60 to remain parallel 55 to the ring 55 and thus exert an even pressure on the entire sealing surface.

The end of the shaft 27 that extends beyond the clamping gland 60 has a driving pulley or gear 70 secured thereto.

From the foregoing it is obvious that the pressure exerted by the spring 44 against the shaft 27 will push the shaft to the left 65 along its axis thereby causing the outer sur-

face of flange 54 to press tightly against the corresponding ground bearing surface of the bearing ring 55. Thus if any fluid or gas leaks into the interior of the annular extension 49 it cannot escape past the bearing ring 70 55 due to the close fit of its sealing surface upon that of the said flange 54. Neither will fluid or gas escape past the joint provided by the packing gasket 53 and diaphragm 58, nor past the inner edge of the diaphragm 75 which is soldered or welded to the sealing ring.

While the form of embodiment of the invention as herein disclosed, constitutes a preferred form, it is to be understood that other forms might be adopted, all coming within 80 the scope of the claim which follows.

What is claimed is as follows:

In combination a casing having an opening in its wall, a rotary shaft extending 85 through the opening and means for sealing the shaft gas tight to the casing including a shoulder on the shaft, a sealing ring frictionally engaging the shoulder, means for urging the shoulder against the ring, a flexible diaphragm supporting the ring, means 90 for clamping the diaphragm gas tight to the casing, said means including an abutment adapted to receive the thrust of the urging means, a rigid thrust member for transmitting the thrust of the urging means to the abutment, and means for maintaining the thrust member parallel to the ring.

In testimony whereof I hereto affix my signature.

CLARENCE WARNER.
